FIG. 1.

FIG. 2.

FIG. 3.

FIG. 4 - 6

GEORGE W. STEIN,
BY Munn & Co.

ATTORNEYS

UNITED STATES PATENT OFFICE.

GEORGE W. STEIN, OF CHICAGO, ILLINOIS.

WINDOW-LOCK.

1,194,089.

Specification of Letters Patent. Patented Aug. 8, 1916.

Application filed February 14, 1916. Serial No. 78,171.

To all whom it may concern:

Be it known that I, GEORGE W. STEIN, a citizen of the United States, and a resident of Chicago, in the county of Cook and State 5 of Illinois, have invented an Improvement in Window-Locks, of which the following is a specification.

This invention is an improvement in locks and has particular reference to a window lock.

An object of the invention is to provide a novel form of lock to be attached either to a window frame or one of the sashes, whereby, in the first instance, the lower sash may be locked in closing position and whereby, in 15 the second instance, the upper sash may be partly lowered and opened, to permit of proper ventilation, and then locked against further opening.

Another object is to provide a lock of this 20 character which is simple in construction, easy to manufacture, and effective in carrying out the purpose for which it is designed.

The inventive idea involved is capable of 25 receiving a variety of mechanical expressions, one of which, for the purpose of illustrating the invention, is shown in the accompanying drawing, in which—

Figure 1 is a front elevation of a window 30 frame and sashes showing the invention applied thereto. Fig. 2 is a section on the line 2—2 of Fig. 1, showing the sashes in closed and locked positions. Fig. 3 is a view similar to Fig. 2 showing the lower sash in 35 locked position and the upper sash opened and locked against further opening. Fig. 4 is a section on the line 4—4 of Fig. 2.

Referring more particularly to the accompanying drawing in which like reference 40 characters indicate similar parts, the numeral 5 indicates a window or sash frame having the upper and lower sashes 6 and 7 slidably mounted therein in the ordinary way.

A plurality of similarly constructed locking devices are preferably attached both to 45 the window frame and the upper sash. The locking devices attached to the window frame are secured to the vertical inner stiles intermediate the ends thereof whereby the upper end of the lower sash may be engaged to lock said sash in closing position. The locking devices secured to the upper sash are adapted to engage the upper end of the 50 lower sash when said upper sash is in both

closed and partially opened positions. Each locking device includes a bracket 8 secured in position by means of a plurality of screws or other fastening elements 9 and upon the inner longitudinal edge of the bracket the same is provided with spaced bearings 10 and 11, the latter being of greater length than the former. The locking member, generally indicated by the numeral 12, consists of an elongated body portion formed from a single length of rod and having its upper end bent laterally at right angles to the body portion to provide a finger piece or grip 13. The upper end of the body portion 12 adjacent the finger piece 70 13 is pivotally mounted in the upper bearing 10 of the bracket 8 and the lower end of said body portion is similarly mounted in the bearing 11. The part of said body portion between the upper and lower bearings 75 10 and 11 is bent to provide an intermediate locking portion 14 which is of angular formation, as shown in Fig. 2, the inner part of the locking portion extending at right angles to the body of the locking member while the 80 extremity 15 of said portion 14 is bent at right angles to said inner part thereof. The lower extremity of each locking member 12 is also bent laterally to provide a lower locking portion 16 having an upwardly and inwardly inclined extremity 17 which may also be employed as a finger grip, if desired.

When both sashes are closed and it is desired to lock the same the locking members 12 secured to the window frame are swung 90 to the position shown in Fig. 2 whereupon the extremity 15 of the locking portion 14 will engage the upper end of the lower sash 7 and prevent the same from being raised. The locking members 12 secured to the upper sash may also be swung to the position shown in Fig. 2 whereupon the lower locking portion 16 thereof will also engage the upper end of the lower sash 7 and not only prevent lowering of the upper sash but also 95 raising of the lower sash. Should it be desired to open or lower the upper sash, for the purpose of ventilation, the locking members 12 secured to the upper sash may be swung to the dotted line position shown at 100 the right in Fig. 4 whereupon the lower locking portions 16 of said locking members will be moved to a position out of alignment with the lower sash and the upper locking portions 14 will be swung outwardly into 105 110

alinement with said lower sash. This will permit of the upper sash being lowered until the bottom of the extremity 15 of the locking portion 14 of each locking member comes 5 into contact with the upper end of the lower sash 7 thus preventing further lowering of said upper sash. By letting the locking members 12 secured to the window frame remain in their original positions, above de- 10 scribed, the lower sash will still remain locked. For purposes of proper ventilation a ventilating screen of any preferred construction may be secured in position at the outer and upper end of the window frame 15 thus covering the opening made by the lowering of the window sash to the position just described. In order to lower the upper sash to its lowermost position, or in other words, completely open the same, the locking members 12 secured to said upper sash must be swung to the dotted line position shown at the left of Fig. 4 whereupon both 20 of the locking portions 14 and 16 will be out of vertical alinement with the lower sash 7 and when in this position said upper sash 6 may be lowered if desired. In order to permit the locking members 12 secured to the upper sash to be swung to the position last described the brackets 8 in which the locking members are mounted are secured to the upper sash adjacent the inner edges thereof 25 so that the extremity 15 of the locking portion 14 will clear the inner edge of the sash

and project inwardly toward the pane of glass.

The lower sash 7 may be opened by moving the locking members 12 secured to the window frame to the dotted line position shown in Fig. 4 whereby said lower sash may be completely opened when the locking members 12 secured to the upper sash are in the position last described. But the opening of the window may be limited by first swinging the locking members 12 secured to the upper sash to the position shown at the right in 40 Fig. 4 whereupon the upper end of the lower sash will contact the locking extremities 15 and thus prevent further opening of said lower sash.

What is claimed is:

A locking device for windows including a pivoted locking member formed from a single length of rod material and bent at one end to provide a locking portion adapted to be swung into and out of the path of movement of one of the sashes, said member also having intermediate its ends another angular locking portion, the extremity of the last-named locking portion extending at right angles to the first-named locking portion, whereby said extremity will be in the path of movement of said sash when the first-named locking portion is out of the path of movement thereof.

GEORGE W. STEIN.
